By his Attorney,
Raymond S. Biddle.

UNITED STATES PATENT OFFICE.

CHARLES H. STONEBRIDGE, OF NEW YORK, N. Y.

COLLAPSIBLE BOX.

SPECIFICATION forming part of Letters Patent No. 760,660, dated May 24, 1904.

Application filed December 18, 1902. Serial No. 135,777. (No model.)

To all whom it may concern:

Be it known that I, CHARLES H. STONEBRIDGE, a citizen of the United States, residing at New York, county and State of New York, 5 have invented certain new and useful Improvements in Collapsible Boxes, of which the following is a specification.

This invention relates to collapsible boxes, and more particularly to collapsible lanterns having a foldable box-like body, and in its more particular embodiment constitutes improvements upon the invention disclosed in prior Letters Patent of the United States issued to me November 27, 1900, No. 662,474. 15 In said former Letters Patent I have disclosed a collapsible lantern-body consisting of a plurality of body members or sections pivotally connected and two of which are detachably pivotally connected by means of securing devices, so that the body members can be folded in compact form one upon the other. Pivotally connected with one of the body members is a top member provided with detachable securing means for connecting it with another 20 of the body members and in operative position, and pivotally connected with said top member is a guard formed of two pivotally-connected members and provided with detachable securing devices for securing it in operative 25 position in connection with the top member. Pivotally connected with one of the body members is a bottom member provided with detachable securing devices for connecting it with another of the body members in operative 30 position, said bottom member also embodying candle-holding devices.

According to the present invention I provide a lantern-body consisting of a plurality of pivotally-connected members adapted to be 35 folded one upon the other without relative separation of any of the same, which result is obtained by proper proportioning and relative arrangement and operative connection of the several members. The securing devices 40 for the bottom member, the top member, and the guard upon the top member are permanently attached, which prevents loss or misplacement of the same and renders the operation of collapsing or setting up more simple 45 and convenient.

The main features of the present invention will be readily understood by reference to said prior Letters Patent and the present drawings, in which latter I have shown principally the features of improvement embodied 55 in the present invention.

Referring to the accompanying drawings, which form part of this specification, and in which like reference characters denote like parts in the several views, Figure 1 is an end view of a collapsible lantern embodying the present improvements and in collapsed position. Fig. 2 is a top plan view of the same. Fig. 3 is a side elevation of the same with the top member and the bottom member in extended position. Fig. 4 is a transverse sectional view taken through the four body members and showing the relative proportions and operative connections of the same. Fig. 4^a is a vertical transverse sectional view taken 60 through the said bottom member and illustrating the operation of placing a candle in a candle-holder with which the bottom member is provided. Fig. 5 is a detail side elevation showing a modified form of construction of 65 the securing devices. Fig. 6 is a view similar to Fig. 4 and showing a modified form of construction of the body members, and Fig. 7 is an end view of the body members shown in Fig. 6, the same being in collapsed position 70 or condition.

Referring with particularity to the drawings, the improved lantern comprises a body portion 1, consisting of a plurality of pivotally-connected side or body members *a*, *b*, *c*, and *d*, a top member 2, pivotally connected with the side member *c* of the body portion, and a bottom member 3, pivotally connected with the side member *b* of the body portion. The top member 2 is provided with a foldable guard 2^a 75 for an air-opening 2^b in the top member. Each of the pivotal connections, four in number, of the four side members *a*, *b*, *c*, and *d*, the pivotal connection of the top member 2 with the side member *c*, and the pivotal connection of the bottom member 3 with the side member *b* consist of 80 a plurality of knuckles 4, formed upon the connected members and fixed pintles 5, 5', 5², 5³, and 5⁴ passing through the several knuckles. 85

The securing devices 6, which are of iden- 90

tical formation in the several embodiments, consist each of a plurality of knuckles 7, formed upon the members to be connected, and a slideable latch 8, which is permanently connected with one of the members in connection with which it is used and coacts with the knuckles 7 upon both members in connection with which it is used. Said latch 8 is preferably formed of a single length of stiff wire 8^a, which is bent into two parallel portions 8^b and 8^c, respectively, connected by a short portion 8^d. The length 8^c is passed through a flange 9, formed upon the member, as 3, with which the latch 8 is connected, and upon either side of the same, so as to be slideable therethrough, and is provided at its outer end with a lip or head 8^e, adapted for engagement with said flange 9 to limit the outward movement of the latch 8. The length 8^b is arranged for slideable play through the several knuckles 7 upon the member, as 3, with which the latch 8 is connected and is permanently installed in one of the same, from which it is prevented from detachment by the lip or head 8^e and its engagement with the flange 9. When the two members, as 3, and the side member 4 are to be connected, the latch 8 is drawn outwardly to the limit of its play, the knuckles of both of the members are fitted together, and the latch 8 is then simply forced inwardly, so as to pass the length 8^b of the same through all of the knuckles 7. The inward movement of the latch 8 is limited by the short connecting length or portion 8^d of the latch 8. This operation is reversed for disconnection of the members. The number of the knuckles 7 and the specific relative arrangement of the same and of the flange 9 may be varied to adapt the securing devices 6 to connection with the several members.

In the modified form of construction shown in Fig. 5 the top member 2 and the side member 4 are shown as detachably connected by securing devices 10, which consist of a depending keeper 11, formed upon the edge of the top member 2 and provided with a slideable hook 12, playing in an elongated slot 13 in the keeper 11, said hook being thus pivotally mounted and adapted for connection with an eye 14, arranged upon the member 4. By employing the securing devices 10 in connection with the side member 4 and the top member 2 and with the side member 3 and the bottom member 3 when the parts are all in collapsed and folded position the top member and the bottom member may be firmly locked in flat connection with said side members 4 and 3, the top member then being connected with the side member 3 and the bottom member with the side member 4.

To enable the side members 4, 3, and 2 to be folded together in flat condition, as illustrated in Figs. 1 and 2, I form the side members 4 and 3 of equal length and the side members 3 and 2 of equal length, but slightly

shorter than the side members 4 and 3. The pintles 5 embodied in the pivotal connections of the side members 4, 3, and 2 are so combined with the knuckles 7 that with the parts in set-up position, as shown in Fig. 4, the side members 4 and 3 overlap the pintle 5 by which they are connected and the pintles 5, 5', 5², and 5³ by which they are connected, respectively, with the members 3 and 2. The side member 3 underlaps the pintle 5 by which it is connected with the side member 2 and extends into alinement with the axis of the pintle 5 by which it is connected with the member 2, and the member 3 underlaps the pintle 5 by which it is connected with the member 4 and extends into alinement with the axis of the pintle 5 by which it is connected with the member 4. This formation and association of the several members results in a substantially rectangular arrangement of the side members when the same are set up and enables them to be folded upon the pintle 5 between the members 4 and 3 as a hinge, the pintle 5 connecting the members 3 and 2 being folded inwardly, so that when the side members are in folded position the members 4 and 3 occupy exterior positions and the members 3 and 2 interior positions.

The candle-holder 15, with which the bottom member 3 is provided, is arranged above an opening 16 in said bottom member, and a plurality of spring-fingers 17 are grouped about the same, said opening 16 being provided with a sliding closure 18, arranged between the bottom member and a keeper 19, connected with the bottom member, as at 20, and upon which latter the spring-fingers 17 are mounted. The opening 16 provides for the insertion and withdrawal of the candle in connecting the same with and disconnecting the same from the spring-fingers 17.

In the construction shown in Fig. 6 of the four body members 4, 5, 6, and 7, 4 is broader and 7 is narrower than 5 and 6, which are the same width. This enables the parts to be collapsed, as indicated by the arrow in Fig. 6, into the positions shown in Fig. 7, in which the pintles 5 lie between the several body members, the entirety being in perfectly flat folded condition. In this construction and arrangement of parts it will be noted that the three body members of lesser width lie within the limits of the points of pivotal connection of said body members of lesser width with said body member of greatest width when all of said body members are folded together in flat contact, the body member 4 being the body member of greatest width.

The operation and advantages of the present improvements will be readily understood by reference to said prior Letters Patent initially referred to and to the preceding description and the accompanying drawings. The side members 4, 3, and 2 of the body portion 1 are readily folded together in flat

position when out of use and when extended into operative position are maintained in such position by connecting the bottom member 3 and the top member 2 with the side members 5 by means of the securing devices 6 or 12. The guard 2^a upon the top member 2 may be similarly secured in extended position by means of its securing devices 6 and may be folded flat upon the top member when out of use.

10 The sliding closure 18 for the opening 16 in the bottom member prevents the dripping of candle-grease from the candle-holder.

I do not desire to be understood as limiting myself to the specific details of construction 15 and association of parts as herein described and shown, but reserve the right to vary the same in adapting my improvements to varying conditions of use without departing from the spirit of my invention or the terms of the 20 following claims.

Having thus described my invention, I claim and desire to secure by Letters Patent—

1. In a device of the class described, a bottom member provided with an opening, a keeper arranged adjacent to said opening and provided with a plurality of spring-fingers constituting a candle-holder, and a slidable closure for said opening arranged between said keeper and said bottom member.
- 25 2. In a device of the class described, a body

portion consisting of a plurality of flat body members pivotally connected together in a continuous series, one of said body members being of greater and one of lesser dimension between its respective points of pivotal connection with the other body members than the similar dimensions of said other body members the pivotal connections being oppositely arranged whereby said body members may be folded together serially in flat contact one 35 with the other and within the limits of the points of pivotal connection with the other body members of said body member of greater dimension.

3. In a device of the class described, a body 45 portion consisting of four body members pivotally connected together in a continuous series, two of said body members being of greater width than the remaining two of said body members whereby said body portion 50 may be folded into flat condition with said body members of greater width exterior of the remaining body members.

In testimony whereof I have signed my name in the presence of the subscribing witnesses. 55

CHARLES H. STONEBRIDGE.
